UNITED STATES PATENT OFFICE.

JOHN MERRY, OF NEW YORK, N. Y., ASSIGNOR TO BIGELOW CARPET COMPANY, A CORPORATION OF MASSACHUSETTS.

DESIGN FOR A RUG.

40,799.

Specification for Design. Patented July 26, 1910.

Application filed June 6, 1910. Serial No. 565,417. Term of patent 3½ years.

To all whom it may concern:

Be it known that I, JOHN MERRY, a subject of the King of Great Britain, residing at New York city, State of New York, have invented a new, original, and ornamental Design for Rugs, of which the following is a specification, reference being had to the accompanying drawing, forming part thereof.

The figure is a plan view of one of the like quarters of a rug, showing my new design.

I claim:

The ornamental design for a rug, as shown.

JOHN MERRY.
